UNITED STATES PATENT OFFICE.

JAMES PATTON TAYLOR, OF ELIZABETHTON, TENNESSEE, ASSIGNOR TO HIMSELF AND NATHANIEL G. TAYLOR, OF SAME PLACE.

IMPROVEMENT IN REPEATING ORDNANCE.

Specification forming part of Letters Patent No. 116,775, dated July 4, 1871.

To all whom it may concern:

Be it known that I, JAMES PATTON TAYLOR, of Elizabethton, in the county of Carter and State of Tennessee, have invented a new and Improved Battery-Gun, of which the following is a specification:

The subject of this invention is a magazine-gun, adapted to deliver fire from a large number of barrels, either simultaneously or successively, as desired, and to maintain such fire for a lengthened period with great rapidity. The gun is constructed with a stationary frame-work of requisite strength, consisting of a breech-plate extending from the breech of the gun proper downward to the level of the magazines, and slotted to permit the rotation of a many-chambered breech-plate, which receives the cartridges from the magazines and carries them up into position for firing; an extension behind the upper part of the breech-plate to contain and guide the firing mechanism; a cradle, which receives the magazines and guides the rammers or feeders by which cartridges are forwarded to the breech-piece chambers; and a brace which connects the said cradle and the breech-extension, and affords a bearing for a compound shaft, through which the chambered breech-piece is revolved and the simultaneous firing mechanism is worked. The barrels are connected to the slotted breech-plate, and are inclosed within a casing. This entire frame-work may rest in front by trunnions in a bracket pivoted vertically in the axle of the gun-carriage, and be supported at back by the elevating screw on the trail, or the gun may be mounted in any other suitable manner. The invention further relates to a magazine-box made in cylindrical form, preferably of wood, with any desirable number of magazines bored therein. This box is provided with sheet-metal caps, to avoid the spilling of the cartridges, said caps being arranged to be taken off after the box is in position. It is also furnished with handles, of any convenient form, to facilitate lifting it or conveying it from place to place. It may, if preferred, be made of sheet-metal tubes, secured between suitable heads. The invention further relates to a feeding apparatus, by which the cartridges are ejected from the magazine-box. The said feeding apparatus consists of a number of rods, one for each magazine, mounted in a suitable head, which may be pressed

forward by a spring of any proper construction, preferably of spiral form. The rods are pointed with rubber or other elastic material, to prevent concussion against the cartridges. As a substitute for this automatic-feeding apparatus having constant spring pressure, I propose, in some cases, to employ a device which will press the cartridges forward at the proper instant to fill the chambers in the revolving breech-piece, and will relieve them from pressure at other times. This device will be made the subject for separate application for Letters Patent. The invention further relates to a many-chambered breech-piece, arranged to revolve within the slotted breech-plate, and made up of a number of sections or clusters of chambers, each cluster containing chambers corresponding in number and position to the magazine and to the barrels of the gun, as will be hereinafter described. The invention further relates to mechanism employed for revolving the aforesaid breech-piece. This consists of a lever, which, in its upward motion, engages automatically with the breech-piece, and is released therefrom in its descent by mechanism hereinafter described. The invention further relates to devices for locking the breech-piece and releasing the same when it is to revolve. The invention further relates to mechanism by which the aforesaid lever may be made, in its return motion, to actuate the firing devices when it is desired to discharge the whole number of barrels simultaneously; and, further, to the particular construction of the simultaneous firing devices. The invention further relates to devices by which the barrels may, when desired, be discharged successively. The invention further relates to a device for ejecting the exploded cartridge-shells from the revolving breech-piece. The invention further relates to a mode of constructing a battery-gun with a cluster of barrels secured between suitable heads and incased in a tight cylinder, so that water may be circulated through the said casing and around and among the barrels, for the purpose of keeping them cool. The invention further relates to appliances for attaching and securing the barrels and keeping them cool. The invention further relates to devices for elevating and depressing and training the gun.

Figure 1 is a perspective view of a battery-

gun illustrating my invention. Fig. 2 is a side elevation of the same. Fig. 3 is a central longitudinal section thereof on the line $x-x$, Figs. 4 and 5. Fig. 4 is a rear elevation. Fig. 5 is a vertical section on the line $y-y$, Figs. 2 and 3. Fig. 6 is a section on the line $z-z$, Fig. 3. Fig. 7 is a longitudinal section on the line $w-w$, Fig. 6. Fig. 8 is a section in the same plane, showing a portion of the chambered breech-piece on a larger scale, and exhibiting, also, the preferred form of the chambers and cartridges and the manner of countersinking the flanges thereof in the chambers. Fig. 9 is an end view of the magazine-box. Fig. 10 is a longitudinal section of the same. Fig. 11 is a face view of a revolving disk employed to operate the firing devices successively. Fig. 12 is a perspective view of a compound shaft, hereinafter described, employed to communicate rotation to the breech-piece and to operate the firing devices. Fig. 13 is a transverse section of a cap and shaft employed to connect or disconnect the simultaneous firing apparatus, as hereinafter described. Fig. 14 is a side elevation of the same. Fig. 15 is a longitudinal section thereof.

A represents an axle resting on wheels C and supporting a bolster or bracket, B, through the medium of a vertical pivot, b. The gun may rest in the said bracket B by trunnions of common form. The trail D is made of heavy wrought iron, and is connected at its forward end directly to the axle A. E is a stationary slotted breech-plate, of steel, forming a frame-work for the attachment of the barrels and for containing and properly covering the chambered breech-piece, which is revolved within the said breech-plate, as hereinafter described. O is a stationary frame, connected, by a strong brace, O', to a plate, V, which, by rods V', is firmly bolted to the breech-plate E. These stationary parts and their connections may preferably be made of steel to give them the desired strength. The barrels G G G, of which any suitable number may be used, are, to their butt-ends, screwed into apertures in the breech-plate E, and at their muzzles are inserted in a plate or head, F, which is fitted within a cylindrical casing, J. This casing may be cast, in brass or other metal, of moderate thickness, so as to be quite light, but somewhat thicker toward the breech than at the muzzle or forward end. At its rear end it is screwed or otherwise fitted within an annular flange or recess in the breech-plate E. For convenience of manufacture the front and rear parts of the breech-plate E may be cast or forged separately and secured together by means of heavy bolts. F' is a rod, passed through an aperture in the center of the front portion of the breech-plate E, within which a head formed on the rear or butt-end of said rod is countersunk, as shown in Fig. 3. The forward end of this rod is passed through an aperture in the center of the head F, and, having a suitable screw-thread cut upon it, receives a nut, f', which is screwed down tightly upon the head, so as to secure the latter firmly in position upon the shoulders which are formed to receive it within the forward end of the casing

J and on the muzzles of the barrels G. The joints between the breech-plate E, casing J, head F, and barrels G, are all closed water-tight by the aid of India rubber or other suitable packing. The barrels may be arranged in any suitable manner in parallel horizontal planes, so as to give them a precisely equal range; but those on each side of the vertical center of the cluster have a slight and slightly-increasing divergence horizontally from said vertical center toward each side. In the present illustration the barrels are supposed to be arranged at their rear ends in concentric circles, but they diverge forward in horizontal planes to adapt them to cover any desired width of field at a given range or distance. This divergence should not exceed ten degrees in the barrels at the extreme sides of the cluster. This will adapt them to cover a field of forty or fifty feet in width at a range of five hundred yards, the shots from all the barrels being delivered approximately in one horizontal plane. H H are water-tanks, furnished with pumps I, by means of which water is injected within the casing J, so as to circulate among and around the barrels, and thus keep them cool during continuous firing and avoid the necessity of any cessation of fire for the purpose of cooling the parts. One or more of these tanks may be employed, the water being returned to the same one or delivered into another tank, if preferred. The barrels are coated on their external surfaces with a suitable varnish, which will resist the corrosive action of water. K represents a chambered breech-piece revolving within the slotted breech-plate E, which breech-plate should be extended at back sufficiently to cover and close the rear of the chambers in said breech-piece as the latter is revolved. The breech-piece K is made up of a number of sections, each containing a cluster of chambers, there being four such clusters in the present illustration. The chambers in each section correspond in number and position to the barrels G, and in operation each cluster is brought up in succession to the firing position by mechanism hereinafter described. L is the magazine-box, which may be made of wood or of sheet-metal tubes secured between suitable heads. The magazines l, whether formed of sheet-metal tubes or by boring a cylinder of wood, are made to correspond in number and position to the chambers within each of the sections of the breech-piece K. M M are caps of sheet metal, which are placed over the ends of the magazine-box L to confine the cartridges within it, said caps being secured in position by lugs or stationary buttons m. The ends of the magazine-box are made slightly concave, as represented in Fig. 10, so that when the cap is pressed inward, as shown in the lower part of said figure, and turned one-fourth round, the resilience of the said cap will cause it to be retained firmly in position over the cartridges. At the upper part of the same figure the cap is shown in its flat condition before being thus depressed and secured by the lug.

In the present illustration each magazine is made to contain ten cartridges. The cartridges

are fed forward automatically by busher-rods n , one to each magazine, attached to a plate, N , which is pressed forward by a spiral spring, N' , upon the rod n' , on which the plate N slides. The rod n' is secured in the stationary framework O , which constitutes a guide or bed for the magazine-box, and should be made of steel, as it requires to be of sufficient strength to support the rear and operative parts of the gun. Catches o are employed to hold the plate N and pusher-rods n in their retracted position when a depleted magazine-box is to be removed and a full one to be introduced. The rotation of the breech-piece K is effected by means of a lever, P , fulcrumed concentrically to the said breech-piece, and furnished near its fulcrum with two spring-pawl, p and p' , which work longitudinally upon the said lever, and are pressed inwardly toward its fulcrum by their spring or springs. For this purpose it is preferred to employ two independent springs of spiral form. These pins engage respectively with ratchet-teeth q and q' upon shafts Q Q' , the construction of which is shown in Figs. 3 and 12. The said shafts are mounted between the plate E and brace O' , and fit one within the other, so that they may turn independently. From the form of the teeth q q' it will be apparent that the upward motion of the lever will rotate the forward shaft Q and impart no rotation to the rear shaft Q' , whereas the downward motion of the lever will rotate the shaft Q' in an opposite direction and impart no motion to the forward shaft Q . A pawl, q^2 , is employed to prevent the shaft Q' turning backward. Any backward motion of the shaft Q is prevented by the device which locks the revolving breech-piece as hereinafter described. The rotation of the forward shaft Q is communicated to the breech-piece K , within which the said shaft is keyed, as illustrated in Fig. 6, or otherwise rigidly secured. At each upward stroke of the lever one cluster of chambers which has been charged from the magazine-box L is carried away therefrom and replaced by another empty cluster; at the same time a cluster which was previously charged is carried forward into position for firing. A downward motion of the lever then, by the movement imparted to the shaft Q' , operates the simultaneous firing devices through the medium of the inclined cam-surfaces q^2 , Fig. 12, which carry forward the lower end of a lever, R , Fig. 3, fulcrumed centrally at r , causing the upper end of said lever to draw back the rod S . Upon the forward end of said rod is a head, S' , with perforations to receive plungers t , which plungers work at their rear ends in the stationary disk or plate U , and at their forward ends are constructed with shoulders t' , against which the head S' is thrown by means of the spiral spring s . The forward ends of the plungers t project through perforations in the breech-plate E , in suitable positions to act upon the flanges of the cartridges. Around the forward ends of the plungers are spiral springs t^2 located within suitable chambers in the breech-plate E , as illustrated in Fig. 3, and pressing backward against the shoulders t' . The combined force of all the

springs t^2 is sufficient to overcome the pressure of the mainspring s^1 , so as, after the instant of firing, to retract the ends of the plungers within the perforations in the breech-plate, causing their inner ends to come flush with the inner surface of said plate, in order that they may offer no obstruction to the rotation of the breech-piece K .

The sectional view of Fig. 8 shows the manner of countersinking the cartridge-flanges within the chambered breech-piece K so as to cause the rear of said breech-piece to work in close contact with the inner surface of the chamber of the breech-plate E . When the lever R draws back the rod S and is again released the impulse imparted by the spring S' to the head S and the momentum of the parts overcome for the instant the backward pressure of the springs t^2 . This produces the necessary percussion upon the cartridge-flanges, after which the plungers are pressed backward, as before stated.

From the above description it will appear that the downward stroke of the lever P will fire simultaneously all the cartridges in one cluster, and thus discharge the whole number of barrels at one instant. If it be desired, instead of this, to discharge the barrels successively, the simultaneous-firing mechanism is disconnected by turning the cap s^3 , through which the lever R acts upon the rod S , until the longitudinal slot s^3 in said cap is brought into position to receive the upper end of the lever R , whereby the said lever will be caused, in its motion, to pass into the said slot, and thus the drawing back of the rod S is avoided. To lock the revolving breech-piece in proper position for firing a notch, k , is formed on the periphery of each cluster or section of the said breech-piece. In these notches engages a catch, k^1 , which is attached to a crescent-shaped lever, K' , Fig. 4. This lever is fulcrumed at k^2 , and is pressed inwardly by the action of a spring, k^3 , to draw the catch k^1 into the notch k as each of the sections comes into horizontal position. Upon the lever P is a spring-catch, p^2 , which, in the downward motion of the lever, is pressed inward, and rides upon the surface of the crescent-lever K' without imparting any motion to said lever. As the lever P reaches the downward extremity of its stroke the spring-catch p^2 slips over the oblique end of the lever K' , and, as the lever P again ascends, the spring-catch p^2 , engaging with the said oblique end, presses the lever K' horizontally outward, so as to throw the catch k^1 out of lock with the revolving breech-piece the instant before the rotary movement is to be imparted to the latter. The spring-catch p^2 then slips off the end of the lever K' , allowing the catch k^1 to rest upon the periphery of the revolving breech-piece; and when the next section of the said breech-piece comes up into horizontal position it presses the catch k^1 outward until the notch k comes opposite the catch k^1 , when the latter engages automatically with said notch, and thereby locks the breech-piece, with its upper section or cluster of chambers, in proper position for firing. k^1 represents a guide, of which one may be employed on each side of the lever P to cause it to move

in a proper path to operate the locking and releasing devices, in the manner above described. The section or cluster of chambers in the breech-piece K which has been discharged passes downward into the horizontal position shown in Figs. 4, 5, 6, and 7, in which position the ejecting devices expel the exploded shells therefrom. These devices are illustrated in Fig. 7. Y represents a rod, carrying a head, Y' , which works within the casing Y^2 , and has attached to it a number of pins or small rods, y' , corresponding in number and position to the chambers in each section of the revolving breech-piece. Z represents a lever, fulcrumed at z^1 , and acted upon by a spring, z^2 , tending to retract the head Y, and thereby draw the rods y' within the casing. Z' is a rod working within the shafts Q and Q' , Fig. 3, and pressed forward by the lower part of the lever R, while the upper end of said lever draws back the pin S for the purpose of retracting the firing devices.

It will thus be apparent that the same motion of the lever R which retracts the firing devices for a new discharge operates to project the pins y' , and, by their action, to eject the exploded shells from the chambers of that section of the breech-piece which was last discharged. A successive or continuous fire may be produced by means of a pinion, v, rotated by a crank, v^1 , Fig. 2, and gearing with a cogged disk, V. Within a cavity in the face of said disk is a number of spring-hammers, v^2 , the heads of which are arranged at distances from the center of the disk corresponding with the radii of the successive circles of barrels. The hammers are thus adapted, each of them, to act successively on all of the plungers t in one of the concentric circles. These hammers are actuated by cams or inclines v^3 , Fig. 3, which, as the disk V is rotated, cause the said hammers to be retracted, and, when they are suddenly released, the resilience of their spring-shanks drives the heads forcibly against the rear ends of the plungers t, and by this means one barrel in each circle may be fired at one time until the whole number has been discharged. The successive or continuous-firing mechanism is contained within a suitable casing, W, constructed to adapt it to be opened, as required, for inspection, cleaning, and repairs. All parts of the gun may be constructed to be readily taken apart, and the entire structure possesses but little complication in comparison with the effectiveness of its operation.

In practice a sufficient number of extra barrels will be kept upon the field, so that, in the event of any derangement occurring, new barrels may be introduced in place of injured ones. This can be readily effected by removing the nut and head F, screwing out the defective barrel, and replacing it by a new one.

For artillery service the arm may be made with a smaller number of rifled barrels of larger caliber, adapted for throwing shells, the other parts being suitably modified. The elevation to obtain the necessary range is regulated by a screw, X, Fig. 3, bearing, through the medium of a wheel, x, on its lower end, upon the trail D, and sup-

porting upon its thread the frame-work O, in which the magazine-box is contained, and which supports the rear of the gun. The training of the gun may be effected, approximately, through the medium of the trail D, in common manner. For accurate sighting a lever, D', is provided, said lever being fulcrumed at its lower end in the trail D, and engaging above in any one of the notches of a rack, d', which is permanently fixed to the frame O. The gun is thus turned upon the vertical pivot b, Fig. 3, the wheel x running on the trail D to avoid too great friction. Instead of this device it is preferred, in some cases, to employ for training the gun a horizontal screw or a vertical shaft, carrying at its lower end a pinion working in a segment-rack. This vertical shaft may be hollow, so as to surround the elevating-screw, or it may work concentrically within the elevating-screw, the latter being hollow. By either of these training devices an accurate sight may be obtained, or the gun may be turned continuously, while a successive discharge of the barrels is kept up, so as to deliver a sweeping fire. The training here referred to may be made the subject of future application for Letters Patent.

The magazine will be charged at the arsenal by any suitable method. This may be performed by automatic machinery provided with a long-chambered box with tubes corresponding in number and position with the magazines in the boxes L. One of the boxes L is placed by hand within the cradle or frame O, the pushing devices N n having been drawn back for this purpose. The lugs N² on the box, fitting in seats prepared therefor in the cradle, act as guides or gauges to determine the correct position of the box. The pushers are then released from the catches o to permit them to act upon the cartridges within the magazine-box. As each empty section of the revolving breech-piece K comes in position in front of the magazine-box the cartridges are fed forward through apertures prepared therefor in the slotted breech-plate E until one cartridge enters each of the chambers. The rotary motion being then imparted to the breech-piece by the mechanism hereinbefore described, the newly-charged section is carried up to a horizontal position, and the charged section which was previously in the last-named position is, at the same time, carried upward immediately behind the barrels in position for firing. As each charged section is carried away from the magazine-box the next empty section succeeds it, and, by covering the front of the apertures through the slotted breech-plate, prevents the forward movement of the cartridges or the feed-rods until the said chambered section reaches its proper position, when the whole number of cartridges can be fed into the chambers simultaneously. This will be understood when it is remembered that no cartridge can move forward without the whole number moving at the same time. The movement of the pushers to feed the cartridges forward may, as before stated, be communicated automatically by the spring N', or intermittently, at the proper periods, by a connection with the

lever P or other moving part of the apparatus, which will be described in a future application for Letters Patent. The lever, having reached the upward termination of the stroke, bringing a charged section into position for firing, as before explained, is then depressed, when, if the cap s^2 is in the position represented in Fig. 3, the downward motion of the lever, acting through the medium of the cams q^1 and q^2 and lever R, will retract the pin S and plungers t until the lever R, escaping from the cam q^2 , will release the rod S and permit the spring s^1 to throw the plungers forward with a sudden impulse and effect the discharge through all the barrels of the gun. This forward movement of the lever, which retracts the rods S, imparts, at the same time, a forward movement to the rod Z', and, through the medium of the lever Z, ejects the exploded shells from the section of the breech-piece which was last before discharged. The manner of discharging the barrels successively has been before explained. The training, elevating, and sighting of the gun may be effected in any common or proper manner. In some cases a sighting-bar will be extended from near the muzzle to the rear part of the slotted breech-plate, or backward beyond the breech of the gun, if it be desired to employ the pendulum-hausse.

I claim as my invention—

1. The slotted breech-plate E, constructed with perforations through the rear plate, as herein specified.
2. In a repeating gun, the stationary cradle or guide-frame O, for holding the magazine-box L, substantially as described.
3. The combination of the brace O', the frame O, and upper stationary parts, whereby the parts are rigidly connected together and a convenient bearing for the shaft is afforded, as explained.
4. The magazine-box, constructed with concave ends and provided with buttons m for securing the caps M, substantially as described.
5. The combination of the slotted and perforated breech-plate E, the revolving breech-piece K adapted for the use of flanged cartridges, the

magazine-box L, and the feeder N n, all constructed and arranged to operate substantially as herein described, for the purposes set forth.

6. The combination of the lever P, pawl p, shaft Q, and ratchet-teeth q, operating substantially as described, to revolve the breech-piece at one motion of the said lever, and to be released therefrom on the return motion.

7. The combination of the lever K and catch k, operating, substantially as described, to automatically lock the revolving breech-piece each time it reaches the proper position for firing.

8. The combination of the lever P and spring catch k² with the segment-lever K and catch k¹, to release the breech-piece when it is to be moved, as explained.

9. The shaft Q, constructed with cams or ratchets q¹ q², in combination with the lever P and the simultaneous-firing devices, as described.

10. The combination and relative arrangement of the plungers t, rod S, and head S', to operate simultaneously on the cartridges, as described.

11. The cap s², combined with the lever R and rod S, to cause the said lever to act upon the said rod or disconnect it therefrom, as described.

12. The pinion v, disk V, hammers v², and cam surfaces v³, combined to effect a successive discharge of the cartridges, substantially as described.

13. The ejecting devices Y¹ y' Z Z', operating substantially as described.

14. The combination of the recessed and perforated breech-plate E, the barrels G screw into said breech-plate, the casing J fitting back within a flange or recess in the front of the breech-plate, the head F fitting upon the ends of the barrels and within the casing J, and the F' and nut f securing the parts together, the whole being arranged, substantially as herein described, to admit of circulating water around the barrels to keep them cool.
